MINING MACHINE

Robert K. Jeffrey, Columbus, Ohio, and Lewis E. Mitchell, deceased, late of Columbus, Ohio, by Richard D. Nichols, administrator, Columbus, Ohio, assignors to The Jeffrey Manufacturing Company, a corporation of Ohio

Original application May 6, 1938, Serial No. 206,448. Divided and this application November 4, 1940, Serial No. 364,325

3 Claims. (Cl. 262—28)

This invention relates to a mining machine and particularly to conduit forming mechanism for conducting hydraulic fluid to hydraulic motor means for adjusting the mining mechanism of a mining machine, which conduit mechanism includes relatively movable parts.

An object of the invention is to provide a mining machine with hydraulic controlling mechanism in which improved conduit forming mechanism for the hydraulic fluid is provided to form a continuous conduit which travels through one or more relatively movable parts of the mining machine and in which the conduit is continuous at all positions of adjustment of said adjustable parts.

Another object of the invention is to provide a continuous conduit forming means between two relatively moving parts which will form a continuous conduit for all relative positions of adjustment of said parts and which will withstand very high hydraulic pressures.

A further object of the invention is to provide improved means for conducting hydraulic fluid to a pivoted or trunnioned hydraulic piston motor.

Another object of the invention is to provide a mining machine which includes a pivoted hydraulic piston motor and improved conduit forming means leading thereto in which provision is made for pivotal movement of the hydraulic motor relative to its support and in which provision is made for swinging of the entire hydraulic motor as a unit while maintaining the hydraulic conduit continuous at all times.

Other objects of the invention will appear hereinafter, the novel features and combinations being set forth in the appended claims.

This application is a division of our application Serial No. 206,448 filed May 6, 1938, for an improvement in Mining machines.

In the accompanying drawings:

Fig. 1 is a diagrammatic plan view showing a mining machine incorporating the structure of our invention;

Fig. 2 is an enlarged plan view showing the forward end of the mining machine with the kerf cutting mechanism cut short;

Fig. 3 is a combination side and sectional elevational view showing the construction of a hydraulic piston motor for swinging the kerf cutting mechanism in its own plane;

Fig. 4 is a transverse sectional view taken on the line 4—4 of Fig. 3 looking in the direction of the arrows;

Fig. 5 is a transverse sectional view through the head of the mining machine; and

Fig. 6 is a piping diagram of a part of the hydraulic system showing certain structural parts thereof diagrammatically.

In Fig. 1 of the drawings there is illustrated diagrammatically a mining machine which incorporates the features of the invention herein claimed. The mining machine is disclosed in 10 full detail in our parent application above identified, of which this application is a division, and so no attempt will be made to describe it in detail in its entirety, only those parts forming the subject matter of the invention herein claimed 15 being specifically described.

Said mining machine includes a truck 45 which supports a turntable 71 upon which is mounted for adjustment in a vertical plane a supplementary frame 100 which has a forwardly extending 20 neck 109 carrying a turnover head mechanism 159 which provides for various adjustments of a kerf cutting mechanism 160.

Extending rearwardly from and supported by the truck 45 is a platform 545 which carries a 25 considerable amount of mechanism which per se is not pertinent to the invention herein claimed.

Attention is directed particularly to Figs. 2 and 5 and to the structure of the turnover head mechanism and the operating means therefor 30 which are adjustably supported with respect to the supplementary frame 100. As seen in Fig. 2 of the drawings, the previously mentioned elongated neck 109 is provided at opposite ends with spaced apart journal bearings upon which is journaled a cylinder 140.

As clearly illustrated in Figs. 2 and 5 of the drawings, the forward and lower end of the cylinder 140 is provided with an integral drum 146 within which drum is rotatably mounted a cylindrical shell 148. The shell 148 is provided with a pair of end plates 149 and 150 which are rigidly but removably attached to said shell 148 as by machine screws 151. It is thus to be seen that the shell 148 provides an enlarged bearing contact with the interior of the drum 146 and is mounted for rotation with respect to said drum 146 about the longitudinal axis of said shell 148 and drum 146.

Adjacent their bottoms the end plates 149 and 150 are provided with semi-cylindrical flanges 152 which cooperate with a flanged split ring 153 rigidly attached to a supporting plate or casting 154 as by screws, which plate 154 carries a cutter bar 156 (Fig. 2) with which is associated a cutter chain 157 provided with cutter bits 158.

It is thus evident that the drum 146, shell 148 and end plates 149 and 150 form the turnover head mechanism 159 which is pivotally adjustable with respect to the longitudinal axis of the neck 109, and that the head mechanism 159 swingably supports a kerf cutting mechanism 160 comprising the cutter bar 156, cutter chain 157 and bits 158, which kerf cutting mechanism 160 is pivotally adjustable with respect to the head mechanism 159 about a generally upright or vertical axis. 10

Cutter chain 157 is driven from an electric motor forming part of supplementary frame 100 and through gearing terminating in shaft 179 and sprocket 187 as fully disclosed in our parent 15 application above identified.

To provide for the adjustment of the kerf cutter mechanism 160 with respect to the turnover head mechanism 159 about the axis of the shaft 179, we provide a pair of hydraulic piston motors 205, best seen by reference to Figs. 2 and 5 of the drawings. The two piston motors 205 are mounted upon opposite sides of the turnover head mechanism 159 and are carried by rearwardly extending arms 206 formed integral with the end plates 149 and 150 of the turnover head mechanism 159. Extending between the two spaced arms 206 and cooperating therewith to support the piston motors 205 is a bracket 207 (Fig. 4) which is rigidly attached thereto as by screws 208. As clearly seen by reference to Figs. 3 and 4 of the drawings, each of the arms 206 cooperates with one end of the bracket 207 to provide a pair of spaced journal bearings 30 adapted to receive trunnions 209 and 210 formed integral with a cylindrical casting 211 of a piston motor 205. It is thus evident that each of the piston motors 205 is mounted for pivotal movement with respect to the turnover head mechanism 159 about a normally upright axis. 35

Each of the piston motors 205 also includes a cylinder 212 rigidly attached to the casting 211 and a removable piston rod head 213. Within the cylinder 212 we provide a piston 214 carried on a piston rod 215. The forward ends of the piston rods 215 of the piston motors 205 are pivotally attached by pins 216 to bifurcated portions 217 of casting 154 forming a part of the kerf cutting mechanism 160, as previously described. 40

It will be evident that by operating the hydraulic piston motors 205 in opposite directions the kerf cutting mechanism 160 may be swung about the axis of the shaft 179.

Attention is now directed particularly to Figs. 3 and 4 and to the construction of the hydraulic conduits leading to the opposite ends of one of the hydraulic piston motors 205. It may be mentioned that each of said hydraulic piston motors 205 is of the double acting type so that hydraulic fluid may be fed under pressure to either end thereof. To provide a conduit leading to the cylinder 212 which will permit pivotal movement thereof about the trunnions 209, 210, trunnion 210 is provided with two drilled passageways 216 and 217, the former of which communicates with a pipe 218 leading to a port 219 in the head end of the cylinder 212. Associated with the passageway 216 is a flexible rubber hose 220 provided with an appropriate fitting 221. Passageway 217 communicates with a longitudinally extending passageway 222 in casting 211 which, in turn, communicates with a port 223 providing communication to the piston rod end of the cylinder 212. A rubber hose 224 is provided with a 75

fitting 225 and communicates with the passageway 217.

Also within the casting 211 and communicating with the piston rod end of cylinder 212 is a passageway 226 leading to an outlet hose 227 provided with an appropriate fitting 228. It is to be noted that the fitting 228 is attached to the casting 211 at a position adjacent the pivotal axis of the cylinder 212.

It may be stated that the two piston motors 205 are of similar but not identical construction and the upper piston motor 205, as viewed in Fig. 2 differs from the piston motor illustrated in Figs. 3 and 4 of the drawings in the following respects. Said upper piston motor 205 is not provided with any passageway similar to passageway 216. It is also provided with a pipe 218' similar to pipe 218 except that said pipe 218' leads to a passageway in the casting 211 which receives a fitting on the opposite end of hose 227 similar to fitting 228. In other words, hose 227 has a fitting at its opposite end from that illustrated in Fig. 4 which is threaded in casting 211 of the upper piston motor 205 which communicates with pipe 218' leading to the head end of the cylinder 212 of said piston motor. The piston rod end of the upper piston motor 205 is connected to a flexible hose similar to hose 224 through passageways similar to passageways 217 and 222 and port 223. The various connections by which hydraulic fluid is supplied to the piston motors 205 are described in full detail in our parent application. 35

To provide for the pivotal movement of the kerf cutting mechanism 160 on the transverse axis of the end plates 149, 150 a hydraulic piston motor 230 (Fig. 2) comprising a cylinder 231 is bolted to the top of cylinder 140 carried on neck 109. The piston motor 230 is of the double acting type and thus the cylinder 231 is provided with inlet ports adjacent its head and piston rod end, respectively. 40

Within the cylinder 231 is a piston mounted upon a piston rod 235 which is connected to a sliding cross-piece 238. The cross-piece 238 is adapted to slide upon a horizontal slideway 241 formed on the top of cylinder 140, said slideway 241 and cross-piece 238 having cooperating locking flange means which provides for free sliding movement between them while holding the cross-piece 238 onto said slideway 241. The cross-piece 238 is provided with trunnions 243 which cooperate with a pair of arms 244 which are pivotally attached by pins 245 (see Fig. 2) to integral bifurcated brackets 246 (Fig. 5) carried adjacent the tops of end plates 149 and 150 of the turnover head mechanism 159. It will thus be evident that by controlling the supply of hydraulic pressure to the piston motor 230 the cross-piece 238 may be slid forwardly and rearwardly or locked in any desired position with a consequent pivotal movement of the kerf cutting mechanism 160 about the axis of the end plates 149, 150. 50

It is evident that the hydraulic piston motor 230 for adjusting the kerf cutting mechanism 160 about the axis of end plates 149, 150 and the hydraulic piston motors 205 for swinging said kerf cutting mechanism 160 about the axis of shaft 179 are both mounted to partake of the rotary motion of the cylinder 140 about the neck 109. Furthermore, there is a pivotal motion between the hydraulic piston motors 205 and the cylinder 140 about the axis of end plates 149, 150. As a consequence, provision must be made for con- 65

necting the hydraulic hoses or conduits to the hydraulic piston motors 205 and 230 while providing for these free pivotal movements. To this end the hoses 220 and 224 lead from the lower piston motor 205, as viewed in Fig. 2, to a swivel cylinder 300, (see Figs. 5 and 6), formed in end plate 159, the axis of which is along the axis of the plate 150.

It may be stated that the hoses 220 and 224 are protected by housing 301 mounted on arm 206 and by housing 302 (see Fig. 2), carried on the forward portion of brackets 245.

Within the cylinder 300 is a cylindrical piston or post 303 provided with longitudinally extending bores 304 and 305. Bore 304 communicates with a circumferential piston ring 306 provided with a circumferential groove 307 in communication with a bore 308 in cylinder 300 which communicates with hose 224. In a similar manner bore 305 communicates with piston ring 309 provided with circumferential groove 310 communicating with bore 311 in cylinder 300 which communicates with hose 220.

Oil seal packing 312 surrounds the piston 303 and provides an oil tight seal between it and the cylinder 300. The packing 312 is removably held in place on the piston 303 by a removable cap 313 attached thereto by machine screw 314.

It will be evident that the piston or cylindrical post 303 may be rotated with respect to the cylinder 300 and yet insure continuous communication between the bores or ports 304 and 308 and between the bores or passageways 305 and 311.

It may also be mentioned that also connected to the bore or port 311 is a flexible rubber hose 315 (Fig. 6) which connects to the piston rod end of the top piston motor 205. This hose 315 (Fig. 6) is protected by housing 316 mounted upon top arm 206, as viewed in Fig. 2 of the drawings. It is thus to be noted that all of the flexible rubber hoses 220, 224 and 315 are fully protected. It may also be mentioned that the rubber hose 227 is protected by the bracket 207, as clearly illustrated in Fig. 4 of the drawings.

Leading from the bores 304 and 305, respectively and rigidly attached to the cylinder or post 303 is a pair of rigid metal hydraulic pipes 317 and 318, the other ends of which are rigidly connected to a block 319 mounted on the cylinder 140, as illustrated in Fig. 6 of the drawings. It is thus evident that a flexible fluid-tight connection is provided between the rigid hydraulic pipes 317 and 318 which are carried by the cylinder 140 and the ports 308 and 311 in the cylinder 300 which is pivotally mounted with respect to said cylinder 140 and which pivots with the kerf cutting mechanism 160 about the axis of end plates 149, 150.

Leading to block 319 and communicating with pipes 317 and 318 are flexible conduits or hoses 321 and 320, respectively, which selectively act as pressure and return lines for that part of the hydraulic system which controls motors 205, as fully disclosed in our parent application above identified.

It is manifest that during the operation of the mining machine the cutter bar 156 may be swung in its own plane in reverse directions by selective operation of the hydraulic motors 205 which may be reversely operated as disclosed completely in our parent application above identified. When in any selective position of adjustment they are locked by trapping the hydraulic fluid therein.

During any swinging movement said motors 205 pivot about their trunnions 209 and 210 and this pivotal movement is freely provided by virtue of the connections disclosed.

5 Swinging movement of the cutter bar 156 in a plane at right angles to its own plane is accomplished by virtue of the double acting piston motor 230, and the hydraulic conduit or path leading from the two rigid pipes 317 and 318 is continuously maintained to the two motors 205 and 206 by virtue of the afore-described conduit forming flexible connection 300, etc., which is so constructed as to form a very high pressure flexible coupling which maintains a continuous conduit between bores 304 and 305 and ports 308 and 311, respectively, at all times. This insures the availability of hydraulic fluid under pressure to operate the hydraulic piston motors 205 at all times without regard to the position 10 of the cutter bar 156 with respect to the turnover head mechanism 159.

Obviously those skilled in the art may make various changes in the details and arrangement of parts without departing from the spirit and scope of the invention as defined by the claims hereto appended, and we therefore wish not to be restricted to the precise construction herein disclosed.

Having thus described and shown an embodiment of our invention, what we desire to secure by Letters Patent of the United States is:

1. In a mining machine, the combination with a frame, of kerf cutting mechanism, means for adjusting said kerf cutting mechanism relative to said frame on angularly related axes including a pivoted hydraulic piston motor for swinging said kerf cutting mechanism on one of said axes, mechanism providing a hydraulic path leading to said motor including a packed piston and cylinder between pivotal parts on the other of said axes.

2. Apparatus of the class described, comprising means providing an interior cylindrical surface having a hydraulic fluid conducting bore 45 communicating with the interior thereof, a piston member mounted in said interior and pivotally adjustable relative thereto about its axis, conduit forming means in said piston member, means including a bored piston ring in said piston providing communication between said bore and said conduit forming means, and packing 50 means forming a high pressure seal between said cylindrical surface and said piston to prevent leakage of hydraulic fluid flowing through said bore and conduit forming means.

3. Apparatus of the class described, comprising means providing an interior cylindrical surface having a hydraulic fluid conducting bore communicating with the interior thereof, a piston member mounted in said interior and pivotally adjustable relative thereto about its axis, conduit forming means in said piston member, means including a bored piston ring in said piston providing communication between said bore and said conduit forming means, and means 60 forming a seal between said cylindrical surface and said piston to prevent leakage of hydraulic fluid flowing through said bore and conduit forming means.
